(57) **CLAIM**

The ornamental design for an end stanchion for vehicular tubular side rail, as shown and described.

DESCRIPTION

FIG. 1 is a perspective view of the end stanchion for vehicle tubular side rail.

FIG. 2 is a front elevational view thereof.

FIG. 3 is a top elevational view thereof.

FIG. 4 is an end elevational view thereof taken from the left end of FIG. 2.

FIG. 5 is an end elevational view taken from the right of FIG. 2.

FIG. 6 is a bottom plan view thereof; and,

FIG. 7 is a perspective view showing the bottom of the end stanchion for vehicular tubular side rail.
